UNITED STATES PATENT OFFICE

FRANK P. RYDER, OF NIAGARA FALLS, NEW YORK

SELF CLEANING, SORTING, OR SIFTING MACHINE

Application filed February 8, 1928. Serial No. 252,819.

My invention relates to self cleaning, sorting or sifting machines adapted to sort out a mass of objects differing in size or shape and of such character that they have a tendency to wedge into and clog the apertures to which they are presented to be sorted or sifted. A particular object of my invention is to provide mechanism which will operate continuously to separate loose green string beans from a mixture of such loose beans and stalks such as is discharged from the stripping rolls of the string bean harvester for which I filed application for Letters Patent of the United States November 9, 1927, Serial No. 232,119. 15 A further object of my invention is to provide mechanism which will separate green string beans into the different sizes required for canning, which will not injure tender beans and will not become clogged by beans of a size 20 too large to pass through the sorting apertures. A further object of my invention is to provide screening mechanism which will successfully assort any mass of objects, whether string beans or other articles, of 25 different sizes and shapes, by presenting them to a series of self cleaning apertures of suitable predetermined sizes.

With the objects above indicated and other objects hereinafter explained in view my invention consists in the construction and combination of elements hereinafter described and claimed.

Referring to the drawings:

Figure 1 is an end view partly broken away 35 of a sorting and sifting machine embodying my invention.

Figure 2 is a side view, partly broken away, of the same.

Figure 3 is a detail view of the ring gear 40 at the front end of the machine.

Figure 4 is a detail view of the ring gear at the rear end of the machine.

Figure 5 is a detail cross sectional view of a portion of the sorting or sifting rollers.

Figure 6 is a detail plan view of the rear end portions of two of the sorting or sifting rollers, and

Figure 7 is a view similar to Figure 6 showing a modified form of rollers.

50 In the drawings 1 indicates a rotary sort-

ing or sifting drum adapted to receive within it a continuous supply of string beans or other objects to be sorted, together with more or less leaves, stalks or other material from which the string beans or other desired articles are to be separated. This rotary drum is provided with end rings 2 and 3, see Figures 1, 2, and 3, and these rings have their bearings on supporting wheels 4 of which there are two for each end ring carried by 55 suitable shafts supported in bearings in the machine frame 5.

End rings 2 and 3 carry respectively externally toothed ring gears 6 and 7, the teeth of which are respectively in mesh with the teeth of driving pinions 8 and 9 which are fast on drive shaft 10 carrying pulley 11 to which power may be supplied from any convenient source. End ring 2 is provided near its outer periphery with openings 12 forming bearings for the front ends of parallel shafts 14 carrying helical or screw elements 13. End ring 3 is provided with inwardly projecting arms 12' having spaces 12' between adjacent projecting arms, see Figure 75 3, so as to permit leaves, stems and string beans too large to pass through the apertures between adjacent screw elements 13 to pass out from the discharge end of the drum. The end rings 2 and 3 are so held by suitable 80 timing of the driving pinions that the bearings for the ends of each of shafts 14 will be in line so that the several shafts 14 will be in line with the axis of the drum. The bearings 12 are so spaced apart that the 85 peripheries of the threads of the helical or screw elements 13 carried by adjacent shafts 14 will be approximately in contact. Each screw carrying shaft 14 is provided at one end outside the end ring 2 or 3, with a gear 15 and the gears 15 of all of the shafts 14 are in mesh with the teeth of an internally toothed stationary ring 16 secured to frame members 17. By suitable adjustment of gears 15 and stationary ring 16, the rotating of shafts 14 90 is so timed that the peripheries of the threads of the screw members 13 of adjacent shafts 14 will be approximately in contact as they rotate. The spaces between the threads of the screw elements of adjacent shafts 14 thus 95 100

form an aperture in the periphery of the rotating drum adapted to permit the passage through them of such of the string beans as are not too large to pass through, it being understood, of course, that passage of the string beans through these apertures takes place only when the particular apertures are, by the rotation of the drum, brought to or near the lowest point in their revolution about the axis of the drum.

10 The size and shape of the apertures formed between the screw elements of adjacent shafts 14 is determined by the size and shape of the helical groove between the threads of the screw elements. In Figure 6 the grooves are shown semicircular so that the aperture formed is round. In Figure 7 the groove is, in cross section, of greater length than depth so as to facilitate the passage from the discharge end of the drum of leaves, stems and string beans which do not readily pass through the apertures between adjacent screw elements 13. The shape of the groove and the resulting aperture formed as above 20 described may be varied to suit the shape of the objects to be assorted.

In operation the rotary drum is rotated in such direction that by their engagement with the teeth of stationary internally 30 toothed gear 16 the gears 15 of the several shafts 14 will cause these shafts to rotate in the direction necessary to feed the mass of objects to be sorted, by contact with the threads of the screw elements 13, towards 35 the delivery end of the drum, that is, towards end ring 3. In order to facilitate delivery of objects which cannot, because of size or shape, pass through the apertures formed between the screw elements of adjacent shafts 40 14, ring 3 is cut away between the bearings 12 of adjacent shafts 14, as shown in Figure 4, so as to present no obstruction to the passage of whatever is carried to the delivery end by the screw elements.

45 The parallel shafts which carry the screw elements 13 being carried on end rings 2 and 3 and the string beans being fed through feed chute 19 to the interior of the drum formed by the shafts and the end rings each 50 pair of shafts with their screw elements will be carried around in a circular path so as to be alternately below and above the mass of string beans. When below the mass, string beans not too large for the apertures will 55 pass through and drop from the drum. When the pair of parallel shafts is above the mass, beans too large to pass through the apertures, the ends of which may have entered the apertures will drop by gravity back 60 into the mass. Each pair of screw elements will thus automatically clean its apertures as, by the rotation of its supporting rings it is revolved about the mass of string beans.

The rotation of the drum 1 tumbles the 65 mass of string beans or other objects to be

assorted, supplied as stated through feed chute 19 at the inlet end of the machine, as it passes from the inlet end of the drum to its delivery end 20 and by reason of this tumbling and the feeding towards the delivery end by the action of the threads of the screw elements, every one of the string beans is practically certain at some point between the inlet end and delivery end of the drum to be presented end on to an aperture so that, if not too large, it will pass through it and will fall through chute 21 into receiving box 28.

70 By reason of the fact that the shafts 14 are all rotated in the same direction the contacting points of adjacent screw elements move in opposite directions as indicated by arrows in Figure 5 so that while one screw element will tend to pull the string bean which has entered the aperture in a direction to move it through the aperture, the other screw element will, on the other side of the aperture, tend to push the bean backward out of the aperture. By reason of this opposition of the two screw elements the tendency 75 to force the bean through an aperture too small to permit it to pass without crushing which might result if the two elements, each constituting half the wall of the aperture, rotated in the same direction is avoided. By 80 reason of this opposition of the moving surfaces of the pair of screw elements there is nothing to hold a string bean in the aperture when the pair of screw elements is above the 85 mass of beans.

If a string bean too large to pass through the aperture should stick in it and fail to drop out when it is carried up to the high point in the revolution of the pair of screw elements forming the aperture, the rotation 90 of these screw elements will carry it along towards the delivery end and ultimately discharge it through one of the openings between the bearings in the rear end ring 3. In order to facilitate the delivery of articles which 95 will not pass through the apertures the threads of the screw elements are cut away as shown at 29 in Figures 6 and 7.

The screw elements 13 are preferably made integral with shaft but may be separately constructed and secured on the shafts.

100 In order to aid in tumbling the mass of string beans or other objects to be assorted and to cause the beans to be presented end on to the apertures, I may provide in line with the axis of the drum a shaft 22 carrying vanes 105 30 and also carrying at one end a gear 27. By means of a sprocket 23 on driving shaft 10 sprocket chain 24 is caused to drive sprocket 25 which carries with it gear 26 in mesh 110 with gear 27, the movement of rotation thus given to the vanes 30 being in the same direction with the rotation of the drum 1 and preferably at slightly higher speed. The vanes 115 30 are preferably corrugated, see 31, Figure 2, so as to form grooves extending radially 120

outward so that as the beans carried upward by the rotation of the drum fall upon these vanes the grooves formed by these corrugations will tend to cause the beans to be pointed radially outward so that their ends will enter the apertures between adjacent screw elements as the beans slide off the vanes. The slightly higher speed of rotation of the vanes obviates any tendency of injury by the vanes to any beans which may have entered an aperture.

Having thus described my invention, what I claim is:—

1. Means for sorting or sifting objects having greater length than thickness comprising a series of parallel shafts carrying screw elements so arranged that the peripheries of the threads of the screw elements of adjacent shafts are approximately in contact and the spaces between their threads on such two screw elements form an aperture for passage of one of the objects to be sorted or sifted, means for rotating said parallel shafts and means for causing said objects to be presented endwise to said apertures.

2. Means for sorting or sifting objects having greater length than thickness comprising a series of parallel shafts carrying screw elements so arranged that the peripheries of the threads of the screw elements of adjacent shafts are approximately in contact and the spaces between their threads on such two screw elements form an aperture for passage of one of the objects to be sorted or sifted, means for rotating said parallel shafts and means for causing said objects to be presented endwise to said apertures comprising a rotary vane having radially extending corrugations.

3. Means for sorting or sifting objects having greater length than thickness comprising a series of parallel shafts arranged to form a hollow cylinder and carrying screw elements so arranged that the peripheries of the threads of the screw elements of adjacent shafts are approximately in contact and the spaces between the threads on such two screw elements form an aperture for passage of one of the objects to be sorted or sifted, and means for rotating said cylinder, and means within said cylinder for causing said objects to be presented endwise to said apertures.

4. Means for sorting or sifting objects comprising a front and rear end ring, a series of parallel shafts having bearings in said rings and forming with said rings a hollow drum, said parallel shafts carrying screw elements so arranged that the peripheries of the threads of the screw elements of adjacent shafts are approximately in contact and the spaces between their threads on such two screw elements form an aperture for passage of one of the objects to be sorted or sifted, means for rotating the rings, means for rotating the parallel shafts, and means within

the hollow drum so formed for tumbling and straightening the objects to be sorted or sifted.

5. Means for sorting or sifting objects comprising a front and rear end ring, a series of parallel shafts having bearings in said rings and forming with said rings a hollow drum, said parallel shafts carrying screw elements so arranged that the peripheries of the threads of the screw elements of adjacent shafts are approximately in contact and the spaces between their threads on such two screw elements form an aperture for passage of one of the objects to be sorted or sifted, means for rotating the rings, means for rotating the parallel shafts, and means within the hollow drum so formed for tumbling and straightening the objects to be sorted or sifted comprising a shaft carrying vanes extending towards the parallel shafts.

6. Means for sorting or sifting objects comprising a front and rear end ring, a series of parallel shafts having bearings in said rings and forming with said rings a hollow drum, said parallel shafts carrying screw elements so arranged that the peripheries of the threads of the screw elements of adjacent shafts are approximately in contact and the spaces between their threads on such two screw elements form an aperture for passage of one of the objects to be sorted or sifted, means for rotating the rings, means for rotating the parallel shafts, and means within the hollow drum so formed for tumbling and straightening the objects to be sorted or sifted comprising a shaft carrying vanes extending towards the parallel shafts having their surfaces corrugated to form radially extending grooves.

7. Means for sorting or sifting objects comprising a front and rear end ring, a series of parallel shafts having bearings in said rings and forming with said rings a hollow drum, said parallel shafts carrying screw elements so arranged that the peripheries of the threads of the screw elements of adjacent shafts are approximately in contact and the spaces between their threads on such two screw elements form an aperture for passage of one of the objects to be sorted or sifted, means for rotating the parallel shafts all in the same direction and in a direction to cause the threads of the screw elements to feed the objects within the drum towards the rear end and means within the drum for tumbling and straightening the objects to be sorted or sifted.

8. Means for sorting or sifting objects comprising a front and rear end ring, a series of parallel shafts having bearings in said rings and forming with said rings a hollow drum, said parallel shafts carrying screw elements so arranged that the peripheries of the threads of the screw elements of adjacent shafts are approximately in contact and

the spaces between their threads on such two elements form an aperture for passage of one of the objects to be sorted or sifted, means for rotating the parallel shafts all in the same direction and in a direction to cause the threads of the screw elements to feed the objects within the drum towards the rear end, the rear end ring being cut away adjacent bearings to provide free passage for objects moved rearward by the screw elements.

9. Means for sorting or sifting objects comprising a front and rear end ring, a series of parallel shafts having bearings in said rings and forming with said rings a hollow drum, said parallel shafts carrying screw elements so arranged that the peripheries of the threads of the screw elements of adjacent shafts are approximately in contact and the spaces between their threads on such two elements form an aperture for passage of one of the objects to be sorted or sifted, means for rotating the parallel shafts all in the same direction and in a direction to cause the threads of the screw elements to feed the objects within the drum towards the rear end, means within the drum for tumbling and straightening the objects to be sorted or sifted and means for rotating the drum.

10. Means for sorting or sifting objects comprising a front and rear end ring, a series of parallel shafts having bearings in said rings and forming with said rings a hollow drum, said parallel shafts carrying screw elements so arranged that the peripheries of the threads of the screw elements of adjacent shafts are approximately in contact and the spaces between their threads on such two elements form an aperture for passage of one of the objects to be sorted or sifted, means for rotating the parallel shafts all in the same direction and in a direction to cause the threads of the screw elements to feed the objects within the drum towards the rear end, means within the drum for tumbling and straightening the objects to be sorted or sifted comprising a shaft concentric with the drum and carrying vanes having radially extending grooves formed therein, means for rotating the drum, and means for rotating the shaft carrying the vanes at a higher speed than that of the drum.

In testimony whereof, I hereunto affix my signature.

FRANK P. RYDER.
